ATTORNEY.

UNITED STATES PATENT OFFICE.

EDGAR P. WILSON, OF LOS ANGELES, CALIFORNIA.

CUTTER.

1,234,846.

Specification of Letters Patent.

Patented July 31, 1917.

Application filed August 1, 1916. Serial No. 112,527.

To all whom it may concern:

Be it known that I, EDGAR P. WILSON, a citizen of the United States, residing at the city of Los Angeles, county of Los Angeles, and State of California, have invented new and useful Improvements in Cutters, of which the following is a specification.

My invention relates primarily to a cutter for use by sign and show card writers, 10 photographers, leather workers and the like, for cutting and decorating purposes, for trimming drawings, photographs and the like and comprises a blade holder adapted to be held in the hand of the user while being used, in which holder any of the well known styles of safety razor blades may be positioned and securely retained therein and at the same time easily and quickly inserted or removed therefrom when desired, together 15 with a guard adapted to be detachably connected to said holder to inclose the exposed portion of the cutting edge of the blade when the blade is not being used or while being carried in the pocket of the user and the object thereof is to provide a 20 device of this character which will be cheap and simple in construction and operation.

A further object is to provide a cutter holder in which the cutters may be easily 25 and quickly inserted therein or removed therefrom when desired.

Another object is to provide a cutter holder which may be adapted to fit different sized blades.

30 A still further object is to provide means whereby the cutting edge of the blade will be inclosed when not in use thereby preventing injury thereto or to the user while being transported from place to place.

40 Further uses and objects will appear hereinafter and while I have shown and described my preferred form of cutter holder it will be understood that I do not limit myself to such construction but various changes 45 may be made in construction and operation without departing from the spirit of my invention.

I accomplish the above objects by the device described herein and illustrated in the 50 accompanying drawings forming a part hereof in which:

Figure 1 is a side elevation of my device with a blade protector in position.

Fig. 2 is a front elevation of Fig. 1.

55 Fig. 3 is an enlarged side elevation of my device ready for use with the blade protector removed.

Fig. 4 is a section on the line 4-4 of Fig. 3.

Fig. 5 is a vertical cross-section of my device showing another form of blade in position.

Fig. 6 is a perspective view of a blade protector.

Fig. 7 shows the blank ready for forming in my blade holder.

Referring to the drawings my blade holder comprises a formed blank 10 of sheet metal or other suitable material, which is bent centrally and longitudinally to form 70 a cylindrical body portion 11 and the legs 12 and 13 thereof extend downwardly in contact with each other and the lower end of leg 13 is bent around the lower end of leg 12 to retain the same in position. Extending 75 upwardly and forwardly from the upper portion of body 11 at one end thereof is a finger rest 14 upon which the finger of the operator rests when the device is in use. Extending rearwardly from the opposite 80 end of leg 12 is a semi-circular finger piece 15 adapted to receive the finger of the operator when the device is in use. Extending forwardly from leg 13 at the same end as finger piece 14 is a V-shaped stop piece 85 16 which is bent at a right angle thereto to extend across the opening between legs 12 and 13. Immediately below stop 16 legs 12 and 13 are cut away at an angle as best shown in Fig. 3 to permit the end of the blade 17 to 90 project therethrough a short distance. Leg 12 has a point 20 pressed inwardly near the edge of the cut-away portion to provide additional tension to hold the blade in place in the holder. A slotted tube 18 having a 95 longitudinal slot 19 of a width equal to the thickness of the blade holder is adapted to fit upon the lower end of the holder as best shown in Fig. 2 to inclose the cutting edge of the blade as a guard against injury to 100 the user while the cutter is being carried in the pocket or otherwise. In using my holder with blades having a backbone the blades will be inserted as shown in Figs. 1 to 4 inclusive but in using a narrow blade 105 not provided with a backbone the guard tube 18 is inserted within body portion 11 to provide backing for the blade as best shown in Fig. 5.

In the use of my device the guard is first 110 removed. The holder is held between the thumb and middle finger with the tip of the forefinger resting upon finger piece 14 and the middle finger within the semi-circular

finger piece 15. The cutter is held at an angle to the material to be cut and is drawn along the same, the forefinger being used to exert the necessary pressure and the middle finger being used to draw the blade along the material to be cut.

Having described my invention what I claim is.

1. A cutter comprising a holder adapted 10 for the reception of a cutter blade, said holder being formed of a single piece of metal bent intermediate its ends to form parallel legs and having a finger piece projecting from the bent portion at one end, and 15 another finger piece projecting from one of the legs at the opposite end; said legs having their corners cut away at one end to expose a portion of the cutting edge of said blade and a cutter blade detachably mounted 20 in said holder; and a detachable guard for the cutting edge of said blade.

2. A safety cutter comprising a holder adapted for the reception of a cutter blade, said holder being formed of a single piece of metal bent intermediate its ends to form 25 parallel sides and having a finger piece projecting from the top thereof at one end, and another finger piece projecting from one of the sides at the opposite end; and a cutter 30 blade detachably mounted in said holder with a portion of the cutting edge thereof at one end exposed; and a detachable shield for said exposed cutting edge.

3. A cutter comprising a holder adapted 35 for the reception of a cutter blade, said holder being formed of a single piece of metal bent intermediate its ends to form an arch spring tending to force the sides of said holder together to grip said blade and 40 having the lower edge of one side bent to overlap the adjacent edge of the other side to close the opening therebetween, said holder having one corner thereof cut away to expose a portion of the cutting edge of said 45 blade and a lug projecting from the front end of one of said sides at the upper termination of the cut away portion bent to project across the opening between said ends to form a stop for the front end of the blade, 50 and a finger rest extending forwardly and upwardly from the front end of the arched portion thereof and a semicircular finger piece extending rearwardly and laterally from the opposite end of one of said sides, 55 substantially as described.

4. The combination with a blade of a holder therefor, said holder being formed of a single piece of metal bent intermediate its ends to form parallel sides, one of said sides 60 being longer than the other and being bent at the lower edge thereof to overlap the lower edge of the other side and close the

opening therebetween, said sides having one corner thereof cut away to expose a portion of the cutting edge of the blade; a lug projecting from the front end of one of said sides at the upper termination of the cut away portion, said lug being bent to project across the opening between said ends to form a stop for said blade; a finger rest extending forwardly at an angle from the front end of the bent portion of said holder and integral therewith; and a semi-circular finger piece extending rearwardly and laterally from the opposite end of one of said sides.

5. The combination with a blade of a holder therefor, said holder being formed of a single piece of metal bent intermediate its ends to form parallel sides, one of said sides 65 being bent to overlap the lower edge of the other side to close the opening therebetween; a lug projecting from the front end of one of said sides bent to extend across the front end of the other side to form a stop for 70 said blade near the top thereof; a finger rest extending forwardly and upwardly from the front end of the bent portion of said holder; a hook-shaped finger piece extending rearwardly and laterally from one of said sides 75 at the rear end thereof; said holder having one corner of the sides thereof cut away to expose a portion of the cutting edge of said blade; a projection extending inwardly from one of said sides near the cut away portion 80 thereof adapted to bear against the side of said blade to prevent accidental displacement thereof; and a tubular guard member having a slit in the sides thereof adapted to be slidably mounted on the lower edge of the 85 holder to cover the exposed portion of said blade.

6. The combination with a blade of a holder therefor, said holder being formed of a single piece of metal bent intermediate its 90 ends to form parallel sides; said sides having one corner thereof cut away to expose a portion of the cutting edge of said blade; a stop formed in said holder at the upper 95 termination of said cut away portion; a finger rest extending forwardly and upwardly from the bent portion of said holder at one end thereof, and a hook shaped finger rest extending rearwardly and laterally from one of said sides at the opposite end of said 100 holder; and a tubular guard member adapted to be slidably mounted on the lower edge of said holder to cover the exposed portion of said blade.

In witness that I claim the foregoing I 105 have hereunto subscribed my name this 12th day of July, 1916.

EDGAR P. WILSON.
